UNITED STATES PATENT OFFICE.

FELIX BENEDICT HERZOG AND SCHUYLER SKAATS WHEELER, OF NEW YORK, N. Y., SAID WHEELER ASSIGNOR TO SAID HERZOG.

ELECTRIC SIGNALING APPARATUS.

SPECIFICATION forming part of Letters Patent No. 690,282, dated December 31, 1901.

Application filed January 25, 1886. Serial No. 189,663. (No model.)

To all whom it may concern:

Be it known that we, FELIX BENEDICT HERZOG and SCHUYLER SKAATS WHEELER, citizens of the United States, and residents of the 5 city of New York, in the county of New York and State of New York, have invented certain new and useful Improvements in Electric Signaling Apparatus, (Case No. 24,) of which the following is a specification.

Our invention relates to apparatus for electrical signaling; and it consists in certain new devices, combinations, and arrangements of parts and specifically in arranging and combining oscillation and vibration determining or limiting apparatus and circuit-closing devices, as herein set forth, and also in certain other features and details of construction and of arrangement, also set forth.

Several forms of apparatus in which part 20 of our invention is embodied are shown in the drawings, to which reference is hereby made and in which like letters represent as nearly as possible parts having similar functions or relations to each other in the different forms.

Figure 1 represents one form in which our invention may be carried out. This is a front view of the controlling apparatus at a sending-station; and Fig. 2 is a side view, with 30 the addition of an operating-knob on the spindle. Fig. 3 shows how our invention may be applied to a closed-circuit system. It also shows various additions to the form of Fig. 1.

Referring to Figs. 1 and 2, A represents a magnet to attract armature B, which terminates in a forked lever-arm C. This acts as an escapement for the ratchet-wheel G, mounted loosely upon a suitable arbor, to 40 which it is indirectly attached by engagement of the pawl T (fixed to it) with the star-wheel R, which is rigidly fastened to the arbor. The wheel G may be considered as performing the functions both of a motor-wheel and 45 of a circuit-controlling wheel. Arranged upon its face are the spots J J, which pass under the contact-maker K as the wheel revolves. The forked lever C bears a contact-point coöperating with another contact 50 mounted upon the fixed spring-contact S and coöperating with it in the manner well known

in automatic rheotomes or vibrating bells. The contact-point mentioned as being on the forked lever or escapement-anchor C is not specifically shown, but is of course so placed 55 on and insulated from the fork (if this is of metal) as to short-circuit the magnet in a manner described hereinafter only when the anchor is attracted, or the same result is obtained if the fork is insulated from the wheel 60 at the points of contact. This insulation may be arranged in various ways well known in the art—as, for instance, by having the points of the anchor made of bone or rubber. The spring P when turned carries with it the arbor W when permitted to do so by the forked lever-escapement C, which is normally held by the retractile spring so as to lock the wheel G, and thus the arbor, and only permits this to turn or advance a step at each 70 vibration, the rate of which vibration being determined by the properly-adjustable pendulum F.

The mode of operation is as follows: As the arbor is turned a full revolution by the person 75 desiring to send a signal (by means of a suitable crank or knob, not shown) and so energizes the spring P, the wheel G does not move with it, as it is locked by the lever-escapement. The apparatus remains in this condition, ready to transmit its signal, until it is released or caused to operate from the receiving-station, which may be done by changing 80 the condition of the circuit so as to cause the magnet A to operate. As soon as this is done 85 the magnet attracts the armature until it reaches the contact-point S, whereupon it becomes short-circuited and the armature is retracted, and at each vibration the wheel G is enabled to advance one step. During these 90 steps whenever a space J passes under the contact-brush a break is made in the circuit, which is noted at the receiving-station by means of suitable mechanism. One form of this is shown at bottom of Fig. 2 as consisting 95 of a high-resistance back-stroke bell in series with a battery and key. When the key is depressed, the current will draw the bell-hammer to the magnets and at the transmitter will cause the oscillation of the armature by the intermittent shunting in and out 100 of the magnet at the contact S and by means

of this oscillation forming an escapement, which permits the wheel to rotate under stress of its motor-spring; but the receiver-bell is not affected by the oscillations, as it is 5 adjusted so that its armature will remain attracted during the decrease in current due to the shunting in of the transmitter-magnet; but it will respond to the total breaks in the current caused whenever a spot J passes under brush K. The oscillations of the transmitter cause the wheel to revolve at a fairly-uniform rate, and hence the pause between the two series of spots will be clearly distinguishable to the ear of the operator, or will 10 show on a recording-register, if such be used at central.

The spots J which produce the breaks are arranged in groups characteristic of the particular box of the system. The receiving- 20 operator is made aware that the entire signal has been transmitted by the fact that a long or final pause succeeds the last impulse of the group; but, if desired, there may be a mechanical stop which prevents the further 25 revolution of the wheel, or, if desired, the mainspring may be long enough to permit several revolutions to be made before it runs down, in which case the receiving operator is 30 made aware of the particular signal intended by the transmitting operator by reason of the number of times that the signal characteristic of the box is repeated.

Fig. 3 shows a second form of apparatus embodying the invention, and the central diagram represents one of a series of similar signal-boxes belonging to a district-telegraph system. These boxes are constructed to send a signal characteristic of each box, and in addition thereto variable signals to indicate various things—as, for example, what is wanted at a station represented by a number corresponding to the fixed number sent by the box. The magnet, arbor, contact-maker, motor, spring, and circuits are generally the same as 45 shown in Fig. 1. Here, however, the act of turning the arbor causes the wheel G to turn and the spaces J J, &c., to pass under the contact-brush during the operation. The system and apparatus shown differ also from that of 50 Fig. 1 in that they may be used so as to operate upon a closed circuit. As described hereinafter, the normal position is such that the magnet is cut out, and hence a closed current may be kept continually in line, and 55 the system will start into operation at the first break caused by the act of starting the mechanism of one of the boxes, as hereinafter described. For many purposes it is preferable to use apparatus such as shown in pending 60 application of F. Benedict Herzog filed September 29, 1884, by which at the first break which occurs the circuit is automatically broken at the receiving-station and remains so broken until closed by the operator there; 65 but the apparatus is equally applicable to the ordinary closed-circuit district-telegraph system, in which case the invention may be said

to operate as an escapement which will be very simple, cheap, and reliable and which serves at the same time for a respond or return signal, as will be hereinafter pointed out. 70

The mode of operation is as follows: The weight Q at end of fork serves to keep the lever mechanically at rest against the contact S, and it will thus short-circuit and cut out 75 the magnet, and thus lessen the resistance in line. In addition to this the tension of the spring P causes the projection L on the wheel G to bear upon the point Y, thus forcing the arm B as far to the left as possible until Q 80 bears upon the wheel G. In setting the instrument the operator turns the arbor by means of suitable crank or arm as far as the desired indication upon the dial, if necessary turning aside the usual limiting-stop F' for 85 the purpose. The first indication upon the dial is so placed as to require him to turn the indicating-arm at least far enough to bring the groups representing the characteristic signal under contact K when the instrument 90 runs down. The thrust of the slope of the teeth of the wheel G against the bevel edge of Q moves this so as to break the circuit at S and makes a new circuit through the magnet, thus energizing this, so as to attract 95 the armature and again close the circuit at S, thus forming a vibrator, substantially as shown in the forms of apparatus before described. Each vibration permits the wheel 100 G to make one step, and thus in time bring under the contact-brush K all of the spaces upon its face. As shown, the shunt and not the main circuit is broken at each vibration, and so there will be no indications upon the receiving apparatus except when the spaces 105 pass under the contact-brush. As shown in the drawings, this will occur first at the group of four spaces, then at the group of two, and then when the single space passes, thus giving the signal "4 21," indicating that box No. 21 110 wants signal "4."

In the form described the main circuit is broken as the apparatus is set to the proper signal; but, if desired, this can be avoided, as follows: At the end D D of the fork the 115 shifting pawl C is pivoted so as to have a motion, as shown. As the wheel is turned when the instrument is set the pawl will take position shown, the effect of which is that whenever contact-brush is over the space the 120 thrust of the teeth of the wheel upon the side of the pawl causes this to move the fork to the left, and thus to close the circuit at S. As the wheel is turned farther the point of the pawl flies into the lowest part of the notch, 125 thus permitting enough movement of the arm B to break the circuit again at S; but as the spaces are so arranged with relation to the notches and their co-operating space that this occurs at the same time when contact K is 130 on the middle and not on the spaces the circuit will not be broken. If desired, the adjustment can be made so that not even a short circuit will be broken at setting; but, this is

not necessary in general. As soon as the crank is released, when the apparatus is properly set, the tension of the spring P turns the wheel until it is obstructed by the point of the pawl C' falling into the notch of the tooth, and thus the wheel G, moving upon the fixed center, pushes the pawl so that it turns upon its pivot as far as it can until it is stopped by the pin E and then takes the position and shape which, coöperating with Q at the other end of the lever and with the alternating attraction and retraction of B, forms the reciprocating escapement for the wheel G. The point H upon arm B serves both as an alarm and as a return signal, enabling the operator to discover if the line is in use before he begins to signal and also to discover after his signal has been transmitted if it has been properly received. If this pin H is grasped by the operator as it projects from the box, he can push it to the right, and thus cause the current to traverse the magnet, and then if the line is being used at the time he will feel the effect on the magnet of the make and break. In the same way if he has transmitted his signal he can feel any signal that may be given by the central operator to indicate the proper reception of the signal. This answering-signal given by the operator may be either fixed or arbitrary or varying, according to the want transmitted, as well as according to the box from which it is transmitted.

The receiving-office apparatus, as shown in Fig. 2, will answer for an open-circuit system with the form just described, and if it be desired to operate the transmitter on a closed-circuit system (as just described) the same apparatus serves, provided the key is kept closed, and then the answer-back signal may be given by breaking the circuit at the key the desired number of times in proper sequence and duration.

What we claim is—

1. The combination substantially as described in a variable-signal transmitter of a step-by-step wheel, means for controlling the signal according to the position of the wheel, a rheotome operated by the driving devices, and a motor controlled by the rheotome. 45

2. A transmitter comprising a rheotome and a step-by-step escapement, a motor-spring, and a magnet, all coöperating to rotate the wheel as a result of the operation of the rheotome, and circuit-controlling elements coöperating with the wheel to produce predetermined signals. 55

Signed at New York, in the county of New York and State of New York, this 22d day of January, A. D. 1886.
